DISPLAY STAND

Harry V. Marsh, Chicago, Ill.

Application January 29, 1932, Serial No. 589,581

6 Claims. (Cl. 211—157)

This invention relates to a stand for the display of articles and has to do more particularly with such a device collapsible in its nature.

It is an object of the present invention to provide a display stand of a fibrous material such as cardboard and which may be collapsed into a flat compact body to adapt it for packing and shipping or for other forms of transportation.

Another object of the present invention is to provide a display stand from a single body of sheet material, the body being of a design readily foldable into the desired assembly.

Another object of the present invention is to provide a display stand with panels as a background for articles placed upon its base in order that those articles may be set off to better advantage.

Another object of the present invention is to provide a stand for the display of articles of merchandise the base of which has sections of different elevations to thereby lend itself to a more attractive and novel arrangement of the displayed articles.

The above objects and other desirable objects are made apparent in the following description where similar reference characters are indicative of the same parts as shown in the accompanying drawing hereby made a part of this specification and in which:

Figure 1 is a perspective view of one embodiment of the invention taken angularly from the front;

Figure 2 is a cross section of the embodiment as taken at the line 2—2 of Figure 1;

Figure 3 is a view taken in angular perspective from the back side of the device;

Figure 4 is an orthographic projection of the invention taken from the back at an early stage of assembly; and

Figure 5 is a plan view of the body of the device as it is struck from the sheet stock material.

Reference may be first had to Figure 5. Here the lines shown as dotted are fold lines, and those heavy lines within the material sheet 10 and shown in full indicate incisions or slits.

In order to arrange the sheet of material 10, which may be any fibrous material adapted to be bent at an acute angle, into the position illustrated in Figure 2, the said sheet is folded upwardly and over one hundred eighty degrees along a fold line 11. When in this position an adhesive material is applied to the side of a section 12 contiguous to a section 13 and includ-

ed between a line 14 and a section edge 15. It will be noted that the sections hereafter referred to by reference character are those areas defined on one or more sides by incisions or folding lines.

Section 13 is the back central panel for the device. To either side of the back section 13 are wing sections 16. Within the lower central portion of the sections 16 are slit-like apertures 17. The apertures 17 have portions at either end directed normally to the central portion thereof in order to strike out a tongue 18. Opening to a lower edge 19 of the wing sections 16 are slits 20.

Diagonal slits 21 separate sections 16 from section 22. A short tongue 23 is effected upon the diagonal edge of each of the sections 22 by a deviation in the slits 21, the tongues being of a length to be snugly accommodated by apertures 17 as will be described later.

Adjacent to the section 12 is a section 24, the two named sections being separated by a fold line 25. Disposed upon either side of the section 24 are sections 26. The outer and lower edges (when the stand is assembled) of the sections 26 carry latches or ears 27, a portion of which extends in parallel proximity to their respective sections 26 to form therebetween slots 28.

When folded over as shown in Figure 4, a suitable adhesive material is applied between section 29 and that part of the sections 26 which overlap the first mentioned section. Thus in the inchoate stage of assembly the material of the stand is attached at three contiguous surfaces, namely, section 13 to the part of section 12 overlapping it, and section 29 to the surfaces of the sections 26 projected thereupon.

With the sections attached as described, the material of the stand still remains in a flat shape occupying but a single plane. The folds now to be described, and as had intermediate the various selected sections, transform the flat body into the stand illustrated in Figure 1.

Assuming the sheet 10, which has been glued or otherwise suitably fastened at the desired areas, to be standing upright upon the edge or fold line 11, a forward force is applied at that fold line. Meanwhile the panels 13 and 16 and the section 12 are maintained in a common vertical plane. The applied force, because of the absence of slippage between the cohering sections, causes all of the sections forwardly moved by that force to be hingedly moved about the bordering fold lines.

Sections 22, 24 and 30 are forced into a position normal to the sections remaining in the vertical position. Concurrently to the forward pivotal movement of the sections 22 and 24 about the fold lines 14 and 25, the sections 26, 29 and 31, retain their vertical position. (See Figure 2.) This is because sections of equal width connect with opposite edges or fold lines of opposed sections. It will be noted in Figure 2 that the sections 12, 22, 24 and 26 enclose a section configuring a parallelogram. Likewise the sections 24, 26, 30 and 31 enclose a space having a section with the opposed sides in parallelism.

Section 30 forms a step and section 31 forms a riser above that step. The fold line 33 pre-determines the place of articulation between the two sections 30 and 31. A platform is provided by the section 22 while the shorter adjacent section 29 serves as a riser above the platform. Section 29 is set off from the sections 22 and 30 by the fold lines 34 and 35, respectively.

Just before the forwardly projected sections reach the horizontal position the wings 16 are swung forwardly about the fold lines 36 until they are brought in contact with the diagonal section edges 37 and 38 which are at that time in a mutual vertical plane. Subsequently, as the latches 27 are carried upwardly, the slits 20 coincide with the slots 28 and finally envelope the shanks 39 of the said latches. Simultaneously the tongues 23 bear upon the flaps 18 to force the latter outwardly. When the tongues 23 have reached the slit like apertures 17, an inward push upon the tongues 18 by means of the ball of the thumb deforms the tongues 18 slightly to bring the upper and free edges thereof beneath the tongues 23. While the tongues 18 are thus disposed with their upper edges beneath tongues 23, the tongues 23 may be inserted through the slit 17.

At this time the stand is locked in place. Movement of the platform 22 laterally of the panels 16 is prohibited by the tongues 23 engaging either the tongues 18 or the upper edges of the apertures 17. This locking position of the tongues 23 within the apertures 17 is maintained by the slots 28 securing the wings 16 against swinging from the position adjacent to the diagonal edges of the step and platform. A forward movement of the section 26, and hence of the step 30, is precluded by the engagement of the slits 20 with the shanks 39 of the latches 27.

To disassemble the device, it is first necessary to reach to the inner side of the sections 16 and push the tongues 18 outwardly beyond the ends of the tongues 23. Access to the inner side of the flaps 18 is readily had by way of the bottom of the device. It is then possible to chronologically lower the platform and step, swing the panels 16 back into alignment with the back panel 13, and force the step and platform downwardly concurrently with the folding of the downwardly moving parts.

The device is flat and compact in its "knocked down" form. Usually the side panels 16 are of less width than the center panel 13 so that they may be interfolded over the front of the center panel after the lower appendage has been disposed out of the way. In this manner, the device is made to take up a small amount of shipping space, and further has its parts ar-

ranged in a manner least subjecting them to damage in transit.

Having thus described my invention, what I claim as new and desire to secure by Letters Patent in the United States is:

1. A display device of folded sheet material which when assembled has a horizontally disposed elevated platform with an upstanding wall at its rear, two opposed side wings, and a step leading upwardly to the platform at its front, comprising a blank having a rectangular section forming said opposed side wings and having vertical slots at the lower edge thereof, the side wings being oblique to said rear wall and converging in the direction of the latter, a platform-forming section integral with said rectangular section and formed of material between said wings, said platform-forming section having oblique edges opposed to said side wings, a series of sections integral one with another and depending from the edge of said platform-forming section, said series including a first section having the same length as the maximum length of said platform, a second section having oblique ends parallel in the assembled device with the oblique edges of said platform but in a lower horizontal plane, a third section of the same length as the maximum length of said second section, a fourth section disposed beneath the device, the width of said fourth section equaling the combined widths of said platform and said second section, a section from said fourth section upwardly turned and engaged and secured to the rear wall of said rectangular rear wall forming section, and extensions turned upwardly from said fourth section into engagement with the second section and secured thereto, there being latch means on said extensions, the slots in said side walls receiving said latch means and cooperating therewith for holding said device in the assembly.

2. A display device which when assembled has a horizontally disposed elevated platform with an upwardly projecting wall at its rear, two opposed side walls and a step leading upwardly thereto at its front, and comprising a blank having a rectangular section forming said upwardly projecting rear wall, wings at each side of and integral with said rectangular section and forming said opposed side walls, the side walls being oblique to said rear wall and converging in the direction of the latter, a platform-forming section integral with said rectangular section and formed of material between said wings, said platform-forming section having oblique edges opposed to said side walls, a series of sections integral one with another and depending from the edge of said platform-forming section, said series including a first section having the same length as the maximum length of said platform, a second section having oblique ends parallel in the assembled device with the edges of said platform but in a lower horizontal plane, a third section of the same length as the maximum length of said second section, a fourth section disposed beneath the device, the width of said fourth section equaling the combined widths of said platform and said second section, an extension from said fourth section upwardly turned and engaging and secured to the rear of said rectangular section, and holding means comprising slots in said wings and projections upon said platform and said fourth section, said projections interlocking with said slots for maintaining the device in assembled relation.

3. A display device which when assembled has a horizontally disposed elevated platform with an upwardly projecting wall at its rear, two opposed side walls and a step leading upwardly thereto at its front, and comprising a blank having a rectangular section forming said upwardly projecting rear wall, wings at each side of and integral with said rectangular section and forming said opposed side walls and having horizontal slots therein, the side walls being oblique to said rear wall and converging in the direction of the latter, a platform-forming section integral with said rectangular section and formed of material between said wings and having oblique edges with tongues thereon insertable into said slots to maintain said platform in a predetermined horizontal position in the assembled device, a series of sections integral one with another and depending from the edge of said platform-forming section, said series including a first section having the same length as the maximum length of said platform, a second section having oblique ends parallel in the assembled device with the edges of said platform but in a lower horizontal plane, a third section of the same length as the maximum length of said second section, a fourth section disposed beneath the device, the width of said fourth section equaling the combined widths of said platform and said second section, an extension from said fourth section upwardly turned and engaging and secured to the rear side of said rectangular section, said bottom forming fourth section having upwardly projecting flaps with hooked latch portions thereon interlocking with said slots in the wings to hold the device in assembled relation.

4. A display device which when assembled has a horizontally disposed elevated platform with an upwardly projecting wall at its rear, two opposed side walls and a step leading upwardly thereto at its front, and comprising a blank having a rectangular section forming said upwardly projecting rear wall, wings at each side of and integral with said rectangular section and forming said opposed side walls, the side walls being oblique to said rear wall and converging in the direction of the latter, a platform-forming section integral with said rectangular section and formed of material between said wings, said platform-forming section having oblique edges opposed to said side walls, and a series of sections integral one with another and depending from the edge of said platform-forming section, said series including a first section having the same length as the maximum length of said platform, a second section having oblique ends parallel in the assembled device with the edges of said platform but in a lower horizontal plane, a third section of the same length as the maximum length of said second section, a fourth section disposed beneath the device, the width of said fourth section equaling the combined widths of said platform and said second section, and an extension from said fourth section upwardly turned and engaging and secured to the rear side of said rectangular section, said bottom forming fourth section having integral flaps at the sides thereof, said flaps being foldable upwardly and having hooked latch portions engaging said wings and cooperating therewith to hold said device in assembled relation.

5. A display device which when assembled has

a horizontally disposed elevated platform with an upwardly projecting wall at its rear, two opposed side walls and a step leading upwardly thereto at its front, and comprising a blank having a rectangular section forming said upwardly projecting rear wall, wings at each side of and integral with said rectangular section and forming said opposed side walls and having vertical slots at the lower edge thereof, the side walls being oblique to said rear wall and converging in the direction of the latter, a platform-forming section integral with said rectangular section and formed of material between said wings, said platform-forming section having oblique edges opposed to said side walls, and a series of sections integral one with another and depending from the edge of said platform-forming section, said series including a first section having the same length as the maximum length of said platform, a second section having oblique ends parallel in the assembled device with the edges of said platform but in a lower horizontal plane, a third section of the same length as the maximum length of said second section, a fourth section disposed beneath the device, the width of said fourth section equaling the combined widths of said platform and said second section, and an extension from said fourth section upwardly turned and engaging and secured to the rear side of said rectangular section, said bottom forming fourth section having upwardly projecting flaps with hooked latch portions thereon interlocking with said slots in the wings to hold the device in assembled relation.

6. A display device which when assembled has a horizontally disposed elevated platform with an upwardly projecting wall at its rear, two opposed side walls and a step leading upwardly thereto at its front, and comprising a blank having a rectangular section forming said upwardly projecting rear wall, wings at each side of and integral with said rectangular section and forming said opposed side walls and having horizontal and vertical slots therein, the side walls being oblique to said rear wall and converging in the direction of the latter, a platform-forming section integral with said rectangular section and formed of material between said wings and having oblique edges with tongues thereon projecting into said horizontal slots, and a series of sections integral one with another and depending from the edge of said platform-forming section, said series including a first section having the same length as the maximum length of said platform, a second section having oblique ends parallel in the assembled device with the edges of said platform but in a lower horizontal plane, a third section of the same length as the maximum length of said second section, a fourth section disposed beneath the device, the width of said fourth section equaling the combined widths of said platform and said second section, and an extension from said fourth section upwardly turned and engaging and secured to the rear side of said rectangular section, and flaps projecting upwardly from said fourth section, each of said flaps being provided with a hooked latch portion interlocking with said vertical slots in said wings.

HARRY V. MARSH. 70
